UNITED STATES PATENT OFFICE.

JOHN A. BOHNSACK, OF CLEVELAND HEIGHTS, OHIO, ASSIGNOR TO THE E. F. HAUSER-MAN COMPANY, OF CLEVELAND, OHIO, A CORPORATION OF OHIO.

SECTIONAL PARTITION UNIT.

Application filed November 23, 1927, Serial No. 235,332. Renewed March 27, 1929.

In metallic partition construction, it has been customary heretofore to provide posts or columns having grooves or spaced shoulders for holding and supporting the panel framing carrying the other structure generally. Such posts required to be of very rugged structure, supporting as they did the stresses of the panelling at large, and both in manufacture and direction, complication and resultant expense was occasioned. In accordance with the present invention, I have devised however a construction in which panel sectional units are self contained and self supporting, eliminating post members as supports, while retaining whatever ornamental form may be desired. A further provision is an adjustable assemblage whereby the required dimension may be directly had for various ceiling heights. Other objects and advantages will appear as the description proceeds.

To the accomplishment of the foregoing and related ends, the invention, then, consists of the features hereinafter fully described, and particularly pointed out in the claims, the following description and the annexed drawings setting forth one of the various ways in which the principle of the invention may be applied.

30 In said annexed drawings:—

Fig. 1 is a front elevation showing a partition wall constructed according to the invention; Fig. 2 is an enlarged sectional detail taken on a plane indicated by the line II—II, Fig. 1; Fig. 3 is a similar sectional detail taken on a plane indicated by the line III—III, Fig. 1; Fig. 4 is a vertical section taken on a plane indicated by the line IV—IV, Fig. 1; Fig. 5 is a perspective view of a sectional unit; Fig. 6 is an enlarged sectional detail showing the connection of the tie rod; Fig. 7 is a fragmentary perspective view showing the assembly of horizontal and vertical elements; Fig. 8 is a front elevation of a complete unit; and Figs. 9 and 10 are sectional details taken on planes indicated by the lines IX—IX and X—X respectively, Fig. 8.

Referring more particularly to the drawings, there is shown in Fig. 1 a partition wall comprising for illustration a door and adjacent sectional units, the latter containing for example two glass lights 2, 3, and one opaque panel 4 of sheet metal, and having vertical stiles 5 with extensions 6, and a horizontal

member or ceiling rail 7, and a horizontal member 9 with cornicing 8, chair rail 10, base rail 11 and mop strip or mold 12.

The panel-stretcher elements 2, 3 or 4 engage at their ends in grooves, as at 13, Fig. 3, in channel-shaped elements 5 or the like, packing strips or putty being employed for tightness. Similarly, the panel stretchers engage in grooves provided in the horizontal members 7, 10, 11, etc., and the assemblage is bound together by suitable ties, for instance tie rods 15 which extend between vertical stile channel members and within the respective horizontal members, as shown more in detail in Figs. 4 and 5. For accommodation to various ceiling heights, the unit is preferably of a telescopic type, stile-channel members 6 being telescopically slidable within stile-channel members 5, Fig. 3, and the respective panel-stretcher elements as required, seating in the grooves 13, 14.

The horizontal rail members are shaped up of sheet metal to a form presenting beveling or beading as may be desired, and of a length to engage between corresponding vertical stile channel members, and convenient engagement being had by means of cleats on the latter. Preferably integral cleats are provided as struck-up tongue-cleats 17 diverging from center line, and the end of the rail member may thus straddle the cleats, as shown more particularly in Figs. 6 and 7, and be held tightly in assemblage by the ties 15.

The horizontal rail member 9 may advantageously be made up of mating channel pieces, held together in suitable manner, and preferably having struck-up tongues *t* upon which cornice members 8, likewise of channel construction may be seated, so as to snap over and engage by their flanges *f* with the tongues *t*. For the convenient placement of panel stretchers, it is advantageous to construct the groove of the receiving members by spaced shoulders 1, *s* being integrally formed, and the other *s'* removable. For this, I prefer to form a narrow slotway *w* in the body of the receiving element, and spaced from the shoulder *s* at suitable distance, and correspondingly the removable shoulder *s'* may then be shaped up to hollow channel form having one lip or flange projecting to engage in the slot *w* when seated down in position.

A sectional unit thus made up may comprise as many panel-stretcher elements as desired, these being seated between the horizontal rail

elements and the vertical channel members or stile channels, the latter being slidably nested as 5, 6, where desired, and such sectional units then may be set up with the mop strip or mold 12 on the floor, and the ceiling rail 7 extended by its extension stile channel 6 to engage the ceiling. An adjacent section 5 may then be positioned to the end thereof, and it will be noticed that complementary stile 10 channels 5 or 6 are thus brought into adjacent position with each other. Suitable binding means, as clips 20 may then be set into the flanges of the complementary stile channel members 5, and the structure then is bound 15 together unit to unit. For a finish, a facing plate 21 may then be set in place with its inturned flanges 21' snapped over the ends 20' of the clips 20, to thereby be held in place. When for any reason it be desired subsequent- 20 ly to remove the facing member 21, this may be done by prying loose from the clip ends 20'. Similarly, for the upper complementary stile channel-members 6, clips 18 may be em- 25 ployed as convenient binding means, and the facing plate 19 may be snapped thereover as a finish.

It will thus be seen that sectional units may be had, capable of assembly to form wall partitions to the extent desired, and by virtue 30 of the telescopic construction, the ceiling height requirement of any particular situation may be simply and completely met. At the same time, by reason of the facing plates 19, 21, and the cornice members 8, a finish 35 effect may be had in detail as desired. For panel-stretcher elements, glass, sheet metal, fiber or other material as individually-preferred may be employed.

Other modes of applying the principle of 40 my invention may be employed instead of that described, change being made as regards the features as set forth, provided the means stated by any of the following claims, or the equivalent of such, be employed.

45 I therefore particularly point out and distinctly claim as my invention:—

1. A metallic partition section comprising 50 a panel stretcher, and vertical end frame members each presenting generally parallel flanges and an intermediate web portion indented with a stretcher-receiving groove, and another set of end frame members each presenting generally parallel flanges and an intermediate web indented with a groove slid- 55 ably fitting the indented portion of the afore- said members.

2. A metallic partition section comprising 60 a panel stretcher, and vertical end frame members each presenting generally parallel flanges and an intermediate web portion indented with a stretcher-receiving groove, and another set of end frame members each presenting generally parallel flanges and an intermediate web indented with a groove slid- 65 ably fitting the indented portion of the afore-

said members, and means for connecting the flanges of opposing end frame members.

3. A metallic partition section, comprising 70 a panel stretcher, and vertical end frame members each presenting generally parallel flanges and an intermediate web portion indented with a stretcher-receiving groove, and another set of end frame members each presenting generally parallel flanges and an intermediate web indented with a groove slidably fitting the indented portion of the aforesaid members, and clips for connecting the flanges of opposing end frame members. 75

4. A metallic partition section, comprising 80 a panel stretcher, and vertical end frame members each presenting generally parallel flanges and an intermediate web portion indented with a stretcher-receiving groove, and another set of end frame members each presenting generally parallel flanges and an intermediate web indented with a groove slidably fitting the indented portion of the aforesaid members, and frictionally held clips for connecting opposing flanges of each set of end frame members independently. 85

90 5. A metallic partition section, comprising a panel stretcher, and vertical end frame members each presenting generally parallel flanges and an intermediate web portion indented with a stretcher-receiving groove, and another set of end frame members each presenting generally parallel flanges and an intermediate web indented with a groove slidably fitting the indented portion of the aforesaid members, clips for connecting the flanges of opposing end frame members, and a face plate over said clips and not a part thereof. 100

95 6. A metallic partition section, comprising a panel stretcher, and vertical end frame members each presenting generally parallel flanges and an intermediate web portion indented with a stretcher-receiving groove, and another set of end frame members each presenting generally parallel flanges and an intermediate web indented with a groove slidably fitting the indented portion of the aforesaid members, clips for connecting each set of end frame members, and a face plate over each such set and separable from the clips. 110

115 7. A metallic partition section, comprising a panel stretcher, and vertical end frame members each presenting generally parallel flanges and an intermediate web portion indented with a stretcher-receiving groove, and another set of end frame members each presenting generally parallel flanges and an intermediate web indented with a groove slidably fitting the indented portion of the aforesaid members, rails engageable between the vertical members of each set, and tie rods within the rails and extending between the vertical members of each such set. 120

125 8. A metallic partition section, comprising a panel stretcher, and vertical end frame members each presenting generally parallel

- flanges and an intermediate web portion indented with a stretcher-receiving groove, and another set of end frame members each presenting generally parallel flanges and an intermediate web indented with a groove slidably fitting the indented portion of the aforesaid members, cleats on the inner faces of said vertical members, hollow rails engageable between said vertical members and straddling said cleats, and tie rods within the rails and extending between the vertical members of each such set. 9. In a metallic partition assembly, units comprising channel shaped sheet metal verticals presenting grooves; grooved hollow horizontal cross members extending between positioning cleats on the web portions of such verticals, one of such horizontals presenting a movable portion to allow insertion of a stretcher; tie rods extending between the web portions of such verticals; removable means for securing opposed flanges of the verticals of adjacent units in spaced relation; and removable face plates for covering such joints. 10. In a metallic partition section, the combination of a vertical frame member, and an extension member slidably adjustable axially therewithin, said extension member being insertable into the framing member through an opening in the lateral face thereof. 11. In a metallic partition; units comprising panel plates, sheet metal channel frame verticals each having a groove and tie rods extending between the verticals on opposite sides of the panel plates, said units being assembled in spaced relation to each other by means of clips engaging the flange portions of said channel verticals. 12. In a metallic partition; units comprising panel plates, generally channel shaped sheet metal verticals each having a groove and tie rods extending between the verticals on opposite sides of the panel plates, said units being assembled in spaced relation by means of clips engaging the verticals; and facing plates covering the juncture between adjacent units and being retained by said clips. 13. In metallic partition construction; panel units consisting of channel shaped sheet metal verticals with cleats or struck up extrusions on their web portions; hollow horizontal cross members positioned against said verticals by means of said cleats or extrusions; and clips securing verticals of adjacent units in spaced relation. 14. In metallic partition construction; panel units consisting of generally channel-shaped sheet metal verticals having a groove, a horizontal member presenting a movable portion and clamped therebetween by means of tie rods, a panel filling element insertable in said grooves by replacement of said movable portion and secured by replacement thereof. 15. In metallic partition construction, panel units comprising channel shaped sheet metal verticals; hollow horizontal cross members extending between the web portions of such verticals; tie rods within said cross members and extending between the web portions of such verticals; and clips securing opposed flanges of the verticals of adjacent units. 16. In a metallic partition construction, panel units comprising channel shaped sheet metal verticals; hollow horizontal cross members extending between the web portions of such verticals; tie rods within said cross members and extending between the web portions of such verticals; removable means for securing opposed flanges of the verticals of adjacent units in spaced relation; and removable face plates for covering such joints.

Signed by me this 7th day of November, 1927.

JOHN A. BOHNSACK.

CERTIFICATE OF CORRECTION.

Patent No. 1,724,821.

Granted August 13, 1929, to

JOHN A. BOHNSACK.

It is hereby certified that error appears in the printed specification of the above numbered patent requiring correction as follows: Page 3, line 65, claim 14, after the word "thereof" and before the period insert the words "and clips locking the verticals of adjacent panel units in spaced relationship"; and that the said Letters Patent should be read with this correction therein that the same may conform to the record of the case in the Patent Office.

Signed and sealed this 1st day of October, A. D. 1929.
